(57) **CLAIM**

The ornamental design for a cargo container as shown and described.

DESCRIPTION

FIG. 1 is a front elevation view of a cargo container showing our new design;

FIG. 2 is a first detail view thereof;

FIG. 3 is a second detail view thereof;

FIG. 4 is a left side elevation view thereof;

FIG. 5 is a right side elevation view thereof;

FIG. 6 is a first rear perspective view thereof, coinciding with the detail view of FIG. 2; and,

FIG. 7 is a second rear perspective view thereof, coinciding with the detail view of FIG. 3.

The broken lines are included for the purpose of showing portions of the cargo container that form no part of the claimed design. Alternating dash-dot-dash lines are included to show boundaries of the claim.
